UNITED STATES PATENT OFFICE.

CHARLES H. SEEGMILLER, OF CHICAGO, ILLINOIS, ASSIGNOR TO LOOSE-WILES CRACKER & CANDY COMPANY, OF KANSAS CITY, MISSOURI, A CORPORATION OF MISSOURI.

CARTON.

SPECIFICATION forming part of Letters Patent No. 759,027, dated Ma. 3, 1904.

Application filed December 19, 1903. Serial No. 185,828. (No model.)

To all whom it may concern:

Be it known that I, CHARLES H. SEEGMILLER, a citizen of the United States, residing at Chicago, Cook county, Illinois, have invented a certain new and useful Improvement in Cartons, of which the following is a full, clear, and exact description, such as will enable others skilled in the art to which it appertains to make and use the same, reference being had to the accompanying drawings, forming part of this specification, in which—

Figure 1 is a perspective view showing the carton closed. Fig. 2 is a perspective view of one end of the carton, showing the top section unlocked and partly raised. Fig. 3 is a plan view of that portion of the blank which produces one end of the top section and the adjacent end of the tuck-flap. Fig. 4 is a fragmentary elevation, chiefly in section, on about the line 4 4 of Fig. 5. Fig. 5 is a fragmentary top plan view of one corner of the carton, the top section being omitted; and Fig. 6 is a sectional plan view of the same corner of the carton on about the line 6 6 of Fig. 4.

This invention relates to improvements in cartons—such, for example, as are commonly employed for packaging crackers and the like—and refers more particularly to cartons which embody means for temporarily locking the top section in closed position.

My object is to provide simple and efficient means for enabling the top section to be readily thus locked and for lessening the liability of the top section to become accidentally unlocked.

To this end the invention consists in the various matters hereinafter described and claimed.

Cartons of the general character of the present are old and well known, and therefore the construction of the major portion of the carton need not be particularly described in this specification, a carton of the general character of the present being disclosed, for example, by the patent to F. M. Peters, No. 621,974, granted March 28, 1899. Such a carton as that to which the present invention relates

comprises, of course, a body portion and a top section which is adapted to close the carton in 50 a manner which is well understood.

The accompanying drawings illustrate the front section 1 and one of the ends 2 of the body portion and also show the top section 3, hinged at its back to the body portion, all as 55 is well known and well understood. As is common in cartons of the general character of the present, a top flap 4 extends inwardly from each end 2, and at the forward or free edge of the top section is a tuck-flap 5, which 60 when the carton is closed lies between the front section 1 and the top flaps 4.

Cartons constructed as thus far described have been upon the market for several years; but they are objectionable in that unless some 65 separate and additional fastening member is employed (such as a string tied about the carton or a band or covering pasted about the same) the top section will not remain in closed position, such top section frequently 70 flying open during handling of the carton. This accidental opening of the carton is highly objectionable during handling of the same at the factory, as it makes it necessary for the various operators to successively close the 75 carton and also makes it liable for the contents of the carton to accidentally fall therefrom before the carton is finally closed by the outer wrapper commonly employed and for the inner wrapper (usually a piece of paraffin-paper having ends folded upon the top of the crackers or other contents) to become disarranged.

Furthermore, with the cartons constructed as above described it has been almost impossible to cause the top section to remain 80 in closed position after the usual outer wrapper has been removed by the purchaser, thus causing the contents of the carton to be at least partially exposed after the customary outer wrapper has been broken. These difficulties have been overcome by providing for 85 temporarily locking the top flap in closed position. This has heretofore been accomplished by producing a slit or kerf 6 at each end of the top section in the line of the bend between 90 the top section 3 and the tuck-flap 5, each slit

or kerf 6 opening upon the end of the top section and extending inwardly a short distance, whereby each end of the tuck-flap becomes a locking-tongue 7. After the carton 5 has been made up and closed in the usual manner, as disclosed, for example, by the said patent to Peters, the operator presses inwardly with his thumbs against the upper corners 8 of the front section, whereby the 10 locking-tongues 7 are forced inwardly and caused to engage under the top flaps 4, the said tongues thus serving to lock the top section in closed position until proper force is exerted to open it. This improvement just 15 described and consisting in providing the kerfs 6 to produce the tongues 7, which engage under the top flaps, is not my invention and is not claimed by me.

In the carton constructed in accordance with 20 my present invention the body portion is provided at each end with a short locking portion 9, whose free or inner end is at an angle to the front edge of the top flap and lies intermediate the ends of the coöperating locking-tongue 7 when the parts are in interlocking 25 position, this inner end being spaced from the inner end of the coöperating locking-tongue. By the expression "spaced from the inner end of the coöperating locking-tongue" it is intended to convey the fact that the inner free 30 end of the locking portion 9 is a substantial distance away from the hinge or bending-point of the coöperating locking-tongue. These locking portions are parts of the top 35 flaps 4 and are conveniently produced by merely cutting a wedge-shaped piece from each top flap to present the recess 10 at the front of each top flap near what may be termed its "outer" end—i. e., the flap end 40 which adjoins the end of the carton. The short portion of a top flap at its front and between the outer end of said flap and said recess in such flap thus becomes a locking portion 9, under which the coöperating locking-tongue 45 is adapted to engage, as clearly shown by the drawings. By reason of these short locking portions the operation of locking the carton is facilitated and all danger of accidental unlocking by reason of the front edge 50 of the top flap forcing the locking-tongue

from locking position is removed, for should the front edge of the top flap not register exactly with the slit or kerf 6 when the locking is about to be effected the locking-tongue when pressed inwardly, as previously described, 55 does not have to lift substantially the whole front portion of the top flap in order to bring the locking-tongue 7 in properly-engaged position, but said tongue has to lift only the short locking portion 9. Furthermore, as the 60 locking portion presents an inner edge extending directly across the locking-tongue when the latter is in locking position and this locking-tongue is not engaged by the front edge of the top flap outward strain upon the top 65 section 3 merely causes the locking-tongue to firmly engage under the locking portion, there being no portion of the top flap to engage the locking-tongue at or near its point of connection with the tuck-flap 5, and thus tend to 70 force said locking-tongue outwardly.

I am aware that minor changes in the construction, arrangement, and combination of the several parts of my device can be made and substituted for those herein shown and 75 described without in the least departing from the nature and principle of my invention.

Having thus described the invention, what is claimed as new, and desired to be secured by Letters Patent, is—

80

In a carton, the combination with a body portion including a front and a back section, end sections, and a top flap having a locking portion whose inner end is at an angle to the front edge of said top flap, of a top section 85 having a tuck-flap fitting between said front section and said top flap and slotted to form in part a locking-tongue positioned to be forced below said locking portion of said top flap, said inner end of said locking portion lying 90 intermediate the ends of said locking-tongue and being spaced from the inner end of said tongue; substantially as described.

In testimony whereof I hereunto affix my signature, in the presence of two witnesses, 95 this 14th day of December, 1903.

CHARLES H. SEEGMILLER.
